UNITED STATES PATENT OFFICE.

GEORGE H. CONRAD, OF JOHNSON CITY, NEW YORK.

ADVERTISING DEVICE.

1,263,210.

Specification of Letters Patent. Patented Apr. 16, 1918.

Original application filed December 22, 1916, Serial No. 138,444. Divided and this application filed July 31, 1917. Serial No. 183,711.

To all whom it may concern:

Be it known that I, GEORGE H. CONRAD, a citizen of the United States, residing at Johnson City, in the county of Broome and State of New York, have invented certain new and useful Improvements in Advertising Devices; and I do hereby declare the following to be a full, clear, and exact description of the invention, such as will enable others skilled in the art to which it appertains to make and use the same.

This invention relates to improvements in an advertising device, being a division of my application filed December 22, 1916, serially numbered 138,444, and its primary object is the provision of a device of this character, whereby apparel and the like may be readily and conveniently displayed.

Another object of this invention is the provision of a movable figure on which may be placed, the apparel and the like for the purpose of advertising the same.

A further object of this invention is the provision of means for supporting the figure in such a manner that this figure will be capable of moving upwardly and downwardly to attract attention thereto.

A still further object of this invention is the provision of an advertising device of the above stated character, which will be simple, durable and efficient, and which may be manufactured and sold at a comparatively low cost.

With these and other objects in view, as will become more apparent as the description proceeds, the invention consists in certain novel features of construction, combination and arrangement of parts as will be hereinafter more fully described and claimed.

For a complete understanding of my invention, reference is to be had to the following description and accompanying drawing, in which:

Figure 1 is a front elevation of an advertising device constructed in accordance with my invention,

Fig. 2 is a longitudinal sectional view of the same,

Fig. 3 is a detail view partly in section of a cam.

Referring in detail to the drawing, the numeral 1 indicates a base having rotatably mounted thereon, a housing 2 as described

and claimed in my co-pending application, 55 and which is rotated by a motor as described and claimed in my co-pending application. A circular housing 3 is secured to the top of the casing 2 for inclosing a block 4 having a cam face 5. A substantially U-shape 60 support 6 is secured to the base 1 and overlies the housing 3 as shown in Fig. 2. An operating rod 7 is pivoted to the substantially U-shape support 6 as shown at 8 and has pivotally secured to its free end, a vertically extending rod 9, which extends through an aperture in the support 6 and is connected to a figure 10, adapted to support apparel or the like. A friction roller 11 is rotatably secured on the operating rod 70 7 and is adapted to engage the cam face 5 of the block 4 as the same travels in the path of a circle with the casing 2, causing the rod 9 to move upwardly and downwardly carrying the figure therewith, thus attracting 75 attention to the apparel or the like carried or supported by the figure.

From the foregoing description taken in connection with the accompanying drawing, it will be noted that a novel form of means 80 has been provided, whereby apparel and the like may be readily advertised by being placed upon the figure and have attention attracted thereto by the movement of the figure.

While I have shown and described the preferred embodiment of my invention, it will be understood that minor changes in construction, combination and arrangement of parts may be made without departing 90 from the spirit and scope of the invention as claimed.

Having thus described my invention, what I claim is:

1. An advertising device comprising a 95 base, a casing rotatably mounted on said base, a support secured to the base and overlying the casing, an operating rod pivoted to the support, a rod pivoted to the operating rod and extending vertically through the 100 support, a figure secured to the last named rod and resting upon the support, and means mounted on the casing for raising the figure upwardly and downwardly upon rotation thereof.

2. An advertising device comprising a base, a casing rotatably mounted on said base, a housing secured to the casing, a sup-

2
port secured to the base and overlying the housing and casing, an operating rod pivoted to the support, a rod pivoted to the operating rod and extending vertically through the support, a figure secured to the last named rod, and a cam block secured to the casing and adapted to move the operating rod upwardly and downwardly to move

the figure in a corresponding direction upon rotation of the casing. 10

In testimony whereof I affix my signature in presence of two witnesses.

GEORGE H. CONRAD.
